UNITED STATES PATENT OFFICE.

JAMES MURDOCK McLEAN AND GEORGE THOMAS MUNN, OF NEW WATERFORD, NOVA SCOTIA, CANADA.

WATCH CHARM AND THE LIKE.

Application filed January 22, 1920. Serial No. 353,372.

To all whom it may concern:

Be it known that we, JAMES M. McLEAN and GEORGE T. MUNN, both subjects of the King of Great Britain, residing at New

5 Waterford, Province of Nova Scotia, Canada, have invented certain new and useful Improvements in Watch Charms and the like; and we do hereby declare that the following is a full, clear, and exact description of the invention, such as will enable others skilled in the art to which it appertains to make and use the same.

10 The present invention has relation to an improved or new article of manufacture of 15 watch charms and seals and the principal object is to provide a device adapted for revolution to bring into view an emblem engraved in part on both surfaces of the revolvable element.

20 A further object of the invention is to provide an attachment of the character described, having a disk revolvably mounted thereon and adapted for revolution to display an emblem.

25 With the above and other objects in view which will hereinafter appear as the description continues, the invention consists of the novel features of construction, combination and formation of parts as will be 30 hereinafter more fully described and particularly pointed out in the appended claim.

In the accompanying drawings has been shown a simple and preferred form of the invention, it being, however, understood 35 that no limitation is necessarily made to the precise structural details herein exhibited, but the right is hereby reserved to any changes, alterations or modifications to which recourse may be had that come within 40 in the scope of the claim without departing from the spirit of the invention or sacrificing the efficiency of the same.

In the accompanying drawings:

45 Figure 1 is a front elevation of the improved charm;

Figure 2 is a rear view of the same;

Figure 3 is an elevation illustrating the emblem in full lines, as it appears when the disk is revolved, and,

Figure 4 is a perspective view of the same. 50

The device comprises a scroll frame 10 formed with an eyelet 11 and having a disk 12 connected thereto by oppositely arranged trunnions 13 which are journaled with the ends 14 of the frame 10, so that the said 55 disk may freely rotate in said frame.

On one side 15 of disk 12 is engraved a portion of an emblem, as in this instance a Masonic emblem. A portion of the square 16, compass 17 and alphabetical symbol G, 60 will appear on side 15 of the disk, while on the opposite side will be engraved a similar compass and square 18 and 19, but in this instance, the letter G will be indistinctly traced. 65

When disk 12 is revolved, as illustrated in Figure 4, the full emblem as indicated in Figure 5, will appear, as the square and compass on the two sides are oppositely disposed. 70

It is obvious that we have provided a novel charm that may be attached to the watch chain by the eyelet 11, and which may be revolved to exhibit a full emblem arranged piece-meal thereon. 75

Having thus fully described our invention, what we claim and desire to secure by Letters Patent is:

A thaumatrope comprising a frame and a disk supported for rotation therein, said 80 disk bearing incomplete and mutually dependent fragments of an emblem on the opposite sides thereof, the fragments on one side intersecting those on the other side.

In witness whereof we have hereunto set 85 our hands.

JAMES MURDOCK McLEAN.
GEORGE THOMAS MUNN.
